DESIGN FOR A CHEST OR SIMILAR RECEPTACLE

Lloyd A. Nelson, San Francisco, Calif.

Application July 15, 1938, Serial No. 78,517

Term of patent 3½ years

To all whom it may concern:

Be it known that I, Lloyd A. Nelson, a citizen of the United States of America, residing in the city and county of San Francisco, State of California, have invented a new, original, and ornamental Design for a Chest or Similar Receptacle, of which the following is a specification, reference being had to the accompanying drawing, forming part thereof.

Fig. 1 is a front perspective view of a chest or similar receptacle showing my new design;
Fig. 2 is a front elevation; and
Fig. 3 is an end elevation thereof.

I claim:

The ornamental design for a chest or similar receptacle, as shown.

LLOYD A. NELSON.
